BEAM DRIVE

Ernest L. Richardson, Melrose, Mass., assignor to
General Electric Company, a corporation of
New York

Application June 1, 1938, Serial No. 211,223

2 Claims. (Cl. 242—65)

The present invention relates to beam drives, that is, to arrangements for driving a beam on which layers of threads or bands of textile or paper are wound as are used in paper and textile mills. In arrangements of this kind the threads or bands of paper or textile are usually fed at substantially constant speed to the beam, onto which they are wound. The circumferential speed of the beam, that is, the speed measured at the circumference of the material wound thereon has to be maintained constant to assure uniform winding and to prevent stretching and tearing of the material being wound. A simple arrangement to assure uniform circumferential speed is to provide a drive mechanism including a driving or batching roll or drum driving the beam by frictional contact with the material wound thereon. The driving force then is determined by the friction between the driving roll and the material wound on the beam in contact with the driving roll. With increasing diameter of the material wound on the beam the friction between the material and the driving roll changes due to increasing weight of the material wound on the beam.

The object of my invention is to provide an improved beam drive arrangement whereby the aforementioned drawback is overcome and the friction between the driving drum and the beam is maintained substantially constant. This is accomplished in accordance with my invention by the provision of an improved support for the beam which exerts a variable force on the beam, varying in response to increase in weight of the beam including the material wound thereon.

For a better understanding of what I believe to be novel and my invention, attention is directed to the following description and the claims appended thereto in connection with the accompanying drawing.

The single figure of the drawing illustrates diagrammatically a beam drive arrangement in accordance with my invention.

The arrangement comprises a beam 10 for receiving layers of thread or bands of textile or paper 11. These layers are wound onto the beam over a guide roll 12. The beam is driven by a drive mechanism which includes a motor 13 driving a roll, sometimes termed a batching roll, 14 by means of a belt 15. The driving roll 14 drives the beam 10 through the frictional contact with the material wound onto the beam. As pointed out above, the driving force then depends upon the friction between the material and the driving roll 14 and to assure proper wind-

ing and to prevent stretching and tearing of the material being wound it becomes necessary to provide supporting means for the beam 10 which supports the beam with a force varying as the weight of the material wound on the beam increases. In the present instance the beam 10 is supported by bearing means 16 secured to a supporting lever 17. The left-hand end of the lever 17 is held on a fulcrum 18. During starting operation the lever with the beam is comparatively light and in order to assure sufficient friction contact between the beam and the driving roll 14, a weight 19 is secured to a right-hand end portion of the lever to bias the beam towards the driving roll 14. A portion of the lever intermediate between the beam and the weight 19 is connected by a pivot 20 to a stem 21 which at its lower end is secured to a piston 22 movable in a hydraulic cylinder or servo motor 23. Fluid under pressure is supplied to the servo motor by a conduit 24 and discharged from the servo motor by a conduit 25. The fluid supply conduit 24 includes an orifice 26 and ahead of the orifice as regards the direction of flow of fluid therethrough a valve 27. The latter is positioned in response to pressure changes ahead of the orifice 26. To this end the valve 27 has a stem 28 connected to a diaphragm 29 forming part of a pressure-responsive device which has a pipe 30 connected to the conduit 24 intermediate the valve 27 and the orifice 26. If the pressure in the conduit 24 increases, the valve 27 is moved towards closing position and if the pressure decreases, the valve 27 is further opened so that the pressure in the conduit near the orifice 26 is maintained substantially constant. The discharge conduit 25 includes a valve 31 with an arm 32 pivotally connected by a link 33 to the right-hand end of the supporting lever 17.

During starting, that is, with little or no material on the beam, the supporting lever 17 is in its lowermost position. In this position the valve 31 is in its opening position, thus affording no restriction to the flow of fluid under pressure through the conduit 25. The pressure then in the cylinder of the servo motor 23 is a minimum and the piston 22 is in its lower end position. As material is wound onto the beam 10 the lever 17 is turned upward, that is, in a counterclockwise direction about its fulcrum 18 and thereby moves the valve 31 from opening towards closing position. During such movement the valve 31 restricts more and more the discharge of fluid from the motor 23 and thereby

causes building up of pressure in the servo motor 23. The piston 22 thereby is forced upward with a force increasing with increasing weight of the beam. In other words, as the weight of the material on the beam increases, an increasing supporting force is exerted on the right-hand end of the beam by the servo motor to the effect that the friction between the beam and the driving roll is maintained substantially constant. Without this additional supporting force exerted by the servo motor the friction between the beam and the driving roll would increase due to increasing weight of the beam which would lead to tearing or stretching of the material being wound.

With my improved beam drive the pressure between the driving roll and the beam is maintained substantially uniform, thus preventing damage of threads, fabric, paper or like fibrous material from crushing due to excessive contact pressure. The tension of threads or like material is maintained substantially uniform also during slight variations in the speed of the driving roll as may be occasioned by slight change in motor speed due to change in load or by belt slippage. In such cases an increase in tension exerts a lifting force on the beam which in turn slightly reduces the contact pressure between the driving roll and the beam and hence reduces slightly the friction, slowing down the beam until the thread tension is restored to the value for which the mechanism was adjusted.

Having described the method of operation of my invention, together with the apparatus which I now consider to represent the best embodiment

thereof, I desire to have it understood that the apparatus shown is only illustrative and that the invention may be carried out by other means.

What I claim as new and desire to secure by Letters Patent of the United States is:

1. Beam drive arrangement comprising a beam for receiving material to be wound thereon, a drive mechanism including a driving roll for frictional engagement with material wound on the beam, a lever supporting the beam, means supporting the lever including a hydraulic motor having a piston with a stem pivotally connected to the lever, and means connected to the lever for varying the pressure in the hydraulic motor in response to movement of the lever. 15

2. Beam drive arrangement comprising a beam for receiving layers of material to be wound thereon, a fulcrumed lever forming a bearing for the beam, a drive mechanism including a driving roll frictionally engaging the material wound on the beam to rotate the beam and to act as a support for the beam and the lever, a weight connected to the lever and biasing the beam towards the driving roll during starting, and means to vary the friction between the beam and the driving roll with increasing weight of the beam comprising a hydraulic motor having a piston with a stem pivotally connected to the beam, a conduit supplying fluid at constant pressure to the motor, a discharge conduit including 20 a valve for the motor having an arm, and a link between the arm and the lever for positioning the valve in response to movement of the lever. 25
